UNITED STATES PATENT OFFICE.

LYMAN P. ARMSTRONG, OF SAN JOSE, CALIFORNIA.

CLAMPING DEVICE.

Application filed March 4, 1926. Serial No. 92,253.

It is the object of the invention to provide a simple, durable, strong and effective clamping device for gripping the edges of bedding to prevent it being kicked loose, and to permit the use of bedding of shorter lengths.

In the drawing.—

Figure 1 is a front elevation of a portion of the foot structure of a bed embodying my invention.

Figure 2 is an end elevation of the same.

Figure 3 is a plan view of a portion of the same.

Referring more particularly to the drawing, I show at 1—1 the two side bars of the bed frame, and at 2 the connecting cross bar at the foot of the frame.

Since the two ends of the foot structure are identical in form and construction the following detailed description of one end applies equally as well to the other end.

Passing upwardly through one bar 1 and the end of the bar 2 mounted thereon is a rod 3 having a lateral offset bend therein at 4 just above the bar 2.

At 5 I show the lower jaw of the device having a groove 6 formed in its end to slidably engage the vertical rod 3, the upper edge of this bar being bevelled as at 7.

At 8 is the central jaw of the device having a groove 9 formed in its end to slidably engage the rod 3.

At 10 I show the top jaw of the device having a groove formed in its end as at 11 to slidably engage the rod 3 and bevelled at its lower edge as at 12.

40 A slot 13 is formed in the end of jaw 10 near its lower edge as shown, and in this slot is inserted a metal element 14 having an orifice 15 formed therein to slidably engage the rod 3 and having an upturned and laterally projecting part 16 provided with an orifice 17 to which a cord 18 may be fastened.

In assembling the device the lower jaw 5 is dropped into position on rods 3-3 and the lower end of the bedding or mattress as the case may be disposed thereon. The central jaw 8 is now dropped into position on rods 3-3 and the lower edge of the bedding disposed thereon as shown. The top jaw 10 is now dropped into position on rods 3-3 and pressed down somewhat the upward thrust of the resilient bedding will tend to force the top jaw 10 upwardly

thereby causing the element 14 to bind upon the rods 3-3 and securely hold the several parts in position.

To release the jaws it is only necessary to pull the cord 18 or tip the element 14 upwardly whereby to permit it to slide freely on the rods 3-3. The jaw elements may now be moved upwardly or downwardly as desired until the elements 14 are released to again bind on the rods 3-3. 65

By forming the offsets 4 in rods 3 they may be turned outwardly as shown or inwardly to accommodate shorter jaw bars, or shorter bedding.

In Figure 4 a fastening device is shown wherein a plate 19 is mounted on a screw 20 inserted in jaw 10 as shown, the plate having an orifice 21 therein through which the rod 3 passes. In this, as in the device above described, the plate will slide freely along the rod when the jaw 10 is pressed downwardly but binds on the said rod when the pressure is upward.

It should also be pointed out that in the embodiment shown in Figure 4 no bed frame is used as hereinbefore described, but the rod 3 is mounted in a member 22 which itself functions as the lower jaw of the device, for use in hammocks and easy chairs. 85

It is to be understood, of course, that while I have herein shown and described but one specific embodiment of my invention, changes in form, construction and method of operation of the device may be made within the scope of the appended claims. 90

I claim:—

1. In a structure of the character described, a jaw member, a pair of spaced parallel rods rising therefrom, a second jaw member having a groove formed in each end thereof to slidably engage the adjacent rod, and having a slot formed therein to intersect each of said grooves, a metal plate loosely mounted in each slot and provided with an orifice through which the adjacent rod passes.

2. A structure of the character described comprising a frame, a pair of spaced parallel rods mounted thereon, parallelly arranged jaw members slidably mounted on said rods, the jaw member remote from said frame having a slot formed in each end thereof, a metal plate loosely mounted in each slot and provided with an orifice through which the adjacent rod passes, and means for tilting the plate in the slot.

3. A structure of the character described comprising a supporting member, a pair of spaced parallel rods rising therefrom, a jaw member having a groove formed in each end thereof to slidably engage said rods in parallel relation to said supporting member and having a slot formed in each end thereof and intersecting said grooves, the upper surface of each slot being formed at right angles to the groove it intersects and the lower surface being formed at an angle thereto, and a metal plate loosely mounted in each slot and provided with an orifice through which the adjacent rod passes. 10
